UNITED STATES PATENT OFFICE.

FREDERICK E. DOMSCHEIT, OF BROOKLYN, NEW YORK.

WINDOW.

Application filed March 30, 1926. Serial No. 98,522.

This invention relates to sliding windows of the type described in my U. S. Letters Patent No. 1,377,619 of May 10, 1921 in which the sashes can be held tightly in their slideways, dispensing with the usual weather strips, and which will permit the slackening of the sashes in said slideways so that said sashes can be easily and quickly removed for cleaning purposes, for moving furniture through the window or in cases of fire or the like.

The main object of this invention is to so improve the patented device that it can readily be applied to existing window frame constructions without requiring any material changes therein or in the window sashes.

Another object is to provide a device whereby the sashes can be automatically fastened in any desired position.

With these and other objects in view my invention consists in the construction, combination and arrangement of parts as will be hereinafter more fully described and defined in the appended claims.

In the accompanying drawings which form part of this specification and in which similar reference characters denote corresponding parts:

Fig. 1 is a longitudinal section of the window showing the sashes in unfastened position.

Fig. 2 is a cross section through the window frame showing the sashes in unfastened position.

Fig. 3 is a longitudinal section on line 3—3 of Fig. 2 but showing the fastening means in locking position and Fig. 4 is a partial cross section similar to Fig. 2 showing the fastening means in operative position.

Referring to the drawings *a* denotes the ordinary window frame made of wood or the like having the usual slideways *b* for the upper and lower sashes *c*. Extending longitudinally through each slideway the length of a sash at one side of the window frame and movably bearing therein is a vertically slidable transversely yielding or expandible housing 10 each composed of two interengaging metal members substantially of U-shaped cross section, a rear member 11 and a front member 12 each formed laterally with oppositely directed flanges 11¹, 12¹ engaging one another.

Since the construction of the yielding

housing for each sash is the same, I will in the following describe only one of them.

This member 11 is slidably engaging the slideway *b* and the members 11 and 12 are normally held in expanded position relative to one another by one or more springs 13 (one only being shown). These springs extend transversely through the space between the members 11 and 12 and bear against the latter. In addition to these springs 13 I provide a spring 14 which, as will be later explained, is adapted to be controlled through manually actuated means to produce a clamping effect on the sash, is mounted centrally of the full length of each slideway, i. e. near the upper end of the socket for the inner sash and near the lower end of the socket for the outer sash. To this end the spring 14 is mounted around a pin 15 which is rotatably borne in the front member 12 and which carries at its rear end a plate 16. The latter is movably mounted in the housing or socket 10 adjacent the rear member or plate 11 and acts as a washer for the rear end of the spring 14. The front end of the spring 14 bears against another washer 17 which is also movably mounted in the housing 10 adjacent to the front plate 12. The rear member 11 of the socket is adapted to be suitably suspended from the corresponding cord *d* carrying the counterweight (not shown).

On the opposite side of the window frame a non-expandible housing 18 is provided for each sash which also extends the length of a sash and which is slidably borne in the slideway *b*, and is suspended from the corresponding cord *d* carrying the other counterweight. The side faces of each sash are rounded or convexed outwardly as at *c* and correspondingly the front face 12^a of the member 12 of the yielding housing and the front face 18^a of the non-expandible housing 18 are hollowed or concaved. The sash may be removably secured in its sockets by lateral pivots 26 projecting therefrom and engaging perforations or slots provided in the opposite housings 10 and 18 as indicated in dotted lines in Fig. 1. In its unlocked or unclamped condition the housing 10 is held expanded by the springs 13, the normal tension of which is such that the sash and with it the housings 10 and 18 thereof can be moved up and down along the slideways *b*. But when the spring 14 is compressed from

the rear, as will be hereinafter described, the front member 12 of the housing 10 will be expanded outwardly or forwardly, as a result of which the sash will be clamped between its housings and the latter fastened in position.

Fixed centrally in and extending transversely of the two adjacent slideways bearing the yielding housings 10 is a plate 19 which longitudinally and centrally is formed with a U-shaped bend 19¹ to fit around the bead or partition *e* dividing said two adjacent slideways. This bead is cut away as at *e*¹ about midways of the plate and the latter itself slotted along the cut out portion and straightened or flattened as at 19² to form a bearing for a pivot 20. The inner face of the slideway at the back of the said plate is cut out as at *a*¹ sufficiently to accommodate a plate shaped lever arm 21 which is fulcrumed on said pivot 20 and which is capable of swinging in vertical direction through the cut out space *a*¹. This lever is adapted to extend across the rear face of the plate and has one of its ends 21¹ extended so as to project forwardly through an arcuate slot *a*² (Fig. 3) provided in the front face of the window frame to be accessible for the manual operation thereof. The plate 19 is provided with two openings 19³ arranged midway one alongside the other in horizontal direction (Figs. 2 and 3), each adapted to coincide with a slideway *b*. The inner or rear member 11 of the housing 10 is cut out at a certain place of its length as at 11² to form a passage for a cam or tongue 22 (Figs. 1, 3 and 4). There may, of course, be more than one cut out part in each member 11 when it is desired to have the sashes fasten at different elevations. Said cam 22 is adapted to act upon the inner washer 16 of the spring 14 to compress the latter when it is desired to clamp and lock the sash against vertical movement. The cam 22 is in form of a plate extending transversely of the slideway, and its inner or rear edge is formed laterally with cylindrical projections 22¹, 22², adapted to serve as pivots and as such rotatively engage ears 19⁴ projecting rearwardly from the plate 19. A spring 23 coiled around one of said pivots and engaging with one end said plate 19 and with its other end abutting against the tongue 22 (Fig. 4) has the tendency to raise said tongue toward the housing so that when the latter is in such position that its opening 11² is just in alignment with the opening 19³ in the plate 19 and with said tongue, the latter will pass through the said openings engaging the rear or inner washer 16 ready to compress the spring 14. The tongue or cam 22 is further provided with a rearwardly projecting nose 22³ which is adapted to engage an opening 21² in the lever arm 21 so that when

said arm is turned vertically on its horizontal pivot 20 it will force said tongue 22 against the washer 16 compressing the spring 14 thereby tightening the member 12 against the sash or when moved in opposite direction it will collapse said tongue so that the latter will lie flat or substantially in a horizontal plane within the corresponding opening 19³ of the plate and out of engagement with the opening 22² of the housing. There are two openings 21² in the lever arm, since there are two tongues 22, one for each expandible housing 10 and for each sash. These two tongues will be operated simultaneously by said lever in the above described manner, so that both sashes will simultaneously become fastened or unfastened. In the present example the openings 11² in the members 11 are arranged so that when both sashes are in closed position the same can be fastened.

In order to make this clamping and fastening of the sashes automatic, I provide the following mechanism.

Pivoted to the lever arm 21 at 21³ and adapted to extend downwardly at the rear of the plate 19 is a resilient element or arm 24. The lower end 24¹ of said member 24 is formed to a cam shaped hook facing the plate 19. The latter for the extent equal to that of the movement of the lever is cut out as at 19⁴ and an opening 11⁴ is provided in said rear plate 11 of the housing 10 at such place, that when after closing the upper sash and moving the lower sash into closing position, said opening 11⁴ will be exposed through the opening 19⁴ of the plate and permit the hook 24¹ of said resilient member 24 which in the unfastened position of the lever 21 projects into the opening 19⁴, to pass into said opening 11⁴. By a continued movement of the lower sash into the closing position the arm 24 will be pulled down thereby also turning the lever 21 into fastening position. As the sash approaches the extreme lower end of the slideway the hook 24¹ owing to its cam shaped outer face sliding over the lower edge of the opening 19⁴ is gradually withdrawn from the opening 11⁴ to lie outside of the housing 10 (Fig. 1). Thus the fastening lever 19 is operated automatically when the sashes are moved into closing position and there is no danger of leaving the sashes unfastened by forgetting to move the lever 19. The unfastening of the sashes can be easily effected by moving the lever in opposite direction, in which it is assisted by the tendency of the springs 23 of the cams 22.

In case there are several fastening positions of the sashes the expandible casing 10 has several openings 11², the casing is correspondingly provided with several openings 11⁴ arranged at corresponding intervals apart in a vertical row to cause the auto-

matic operation of the levers for the different positions.

It will be noted that in order to permit the removal of the sashes from the housings sufficient play must be provided to the expansible housings. But due to this play an opening 25 is formed between the front face of the bead *e* and rear faces *c*¹ of the window sashes through which air and rain could 10 pass. To remedy this, one of the housings 10, in this example the housing 10 for the lower sash, is provided with a lateral extension 10¹ of substantially square shaped cross sections (Figs. 2 and 3) and of a length 15 equal to that of the recess formed by the cut away portion *e*¹ of the bead so as to more or less snugly fit therein. When the sashes are clamped by the expansion of the housing 10 this extension 10¹ will just lie flush with 20 the front face of the bead *e*. When it is desired to remove the sashes from their housings, the sashes will have to be first brought into closing position, so that the extension 10¹ will be in alignment with the cut away part *e*¹. In this position the sashes can be pressed laterally in the direction of the yielding housings 10, the extension 10¹ being thereby caused to pass into the recess 25 *e*¹. In this position the sash can be removed 30 first from the stationary housing 18 and then from the yielding housing 10.

Suitable friction actuated means may be provided to prevent the housings 10, 18 from sliding up in the slideways under the action 35 of the counterweights, after the sashes have been removed from their housings.

When for washing the windows it is not desired to remove the sashes entirely from their housing, the same can be just swung 40 inwardly on their pivots 26, after the expansible housings 10 have been unclamped or slackened. Since various changes may be made in the construction without departing 45 from the principle of my invention, I do not wish to limit myself to the details shown and described.

What I claim is:—

1. In a window, the combination with a sash and its slideways, of a rigid counterbalanced housing vertically slidable in one of said slideways, a transversely expansible counterbalanced housing vertically slidable in the opposite slideway, both said housings engaging the sides of said sash and means for expanding and fastening said expansible housing to tighten and fasten the sash in position.

2. In a window the combination with a sash, of a transversely expansible housing 60 for one side of said sash, means for expanding said housing to tighten said sash and means for automatically operating said first named means.

3. In a window the combination with a 65 sash, of a transversely expansible housing

for one side of said sash, means for expanding said housing to tighten said sash, said means including a collapsible cam member, means for manually operating said members and means automatically controlled by said 70 sash and adapted to automatically operate said first named means when said sash is moved into closing position.

4. In a window the combination with a sash, of a transversely expansible housing for 75 one side of said sash, means for expanding said housing to tighten said sash said means including a collapsible spring actuated member, a manually operated lever carrying said member and an element connected to said lever and controlled automatically by said sash so that when the latter is moved into closing position it will automatically operate said lever to expand said housing.

5. In a window the combination with a sash, of a transversely expansible housing for one side of said sash composed of two movably interengaging sections, means normally holding said sections expanded and 90 means for automatically operating said first named means for tightening said housing against the sash.

6. In a window the combination with a sash, of a transversely expansible housing 95 for one side of said sash composed of two movably interengaging sections, means for normally expanding said sections and means for automatically tightening said sections in extended position.

7. In a window, a housing for a sash comprising two transversely expansible interengaging members each of the length of a sash, the rear member being adapted to be suspended from the counterweight, a resilient 105 member carried by the front member, means for actuating said resilient member to expand said housing and a manually operated lever for controlling said first-named means.

8. In a window, the combination with a sash, of a slideway therefor having an opening, a transversely expansible housing of the length of said sash vertically slidable in said slideway, said housing comprising two interengaging members of which the rear member is adapted to be suspended from the counterweight and has an opening, a resilient member carried by said front member, a tiltable member capable of passing through said openings and of actuating said resilient member thereby expanding and fastening said housing and a manually operated lever controlling said tiltable member.

9. In a window the combination with a sash, of a slideway therefor having an opening, a transversely expansible housing of the length of said sash vertically slidable in said slideway, said housing comprising two interengaging members of which the rear member is adapted to be suspended from the 125

counterweight and has an opening, a resilient member carried by said front member, a spring actuated vertically swinging cam member capable of passing through said openings and of actuating said resilient member thereby expanding and fastening said housing and a vertically swinging lever controlling said cam member.

10. In a window, the combination with a sash and a slideway therefor, an expan-

sible housing engaging one side of said sash and slideable within said slideway, means for expanding said expansible housing, a manually operated lever for actuating said means and a resilient means operatively connected to said lever and capable of effecting the automatic operation of said lever. ¹⁵

In testimony whereof I affix my signature.

FREDERICK E. DOMSCHEIT.
